UNITED STATES PATENT OFFICE.

DWIGHT RUSSELL, OF MILFORD, MASSACHUSETTS.

IMPROVEMENT IN VAPOR-INHALERS.

Specification forming part of Letters Patent No. 50,735, dated October 31, 1865.

To all whom it may concern:

Be it known that I, DWIGHT RUSSELL, M. D., of Milford, in the county of Worcester and State of Massachusetts, have invented an Improved Instrument for the Inhalation of Medicated Air or Vapor, such instrument being specially useful in the cure or alleviation of catarrh or various other diseases of the mucous membranes of the human system; and I do hereby declare the said invention to be fully described in the following specification, and represented in the accompanying drawings, of which—

Figure 1 is a side elevation; Fig. 2, a front view, and Fig. 3 a longitudinal section of it. Fig. 4 is a top view of its nose-jets. Fig. 5 is a section of such jets.

The whole of the said instrument is to be made of glass, porcelain, or other suitable material, glass being preferred.

A represents a glass bottle or vessel provided with a long tubular neck, *a*, which at its top terminates in two branches or jet-tubes, *b*, which are to be formed so as to fit into the nostrils of a person. Each of the branches *b* is open at its upper end, as shown at *d*. A tube, *c*, leads out of the bottom of the vessel *A*, and is formed with a bend, *f*, and thence turns upward alongside of the vessel *A* in manner as shown in the drawings, such tube being open at its upper end. There is also a hole, *e*, made through the side of the vessel *A* in a convenient position to be covered by the index-finger of a person's hand when grasping the vessel *A* and applying the branch-tubes to the nostrils.

From the above it will be seen that my inhaler has no open mouth to receive a stopper and the nasal and air tubes, as is the case with most if not all the inhalers, but the nasal jets

or branches *b* are applied directly to and are a continuation of the neck *a*; and, furthermore, the air-supplying tube *c* of my inhaler, instead of being introduced into the neck of the vessel to hold the liquid for medicating the air during the process of drawing it into and through the vessel, passes out of its bottom, and so curves upward or has a duplex flexure, *f*, that the liquid poured through such tube and the vessel *A* will stand in both of them and in the flexure *f*.

This arrangement of the tube enables a very small quantity of liquid to be used in the vessel and greatly increases the distance for the passage of air through the fluid with respect to what would result were the air-pipe to enter the vessel in the ordinary manner. Besides, with my arrangement of the tube *c* it may be employed as a spout for discharging the fluid from the vessel *A* as well as for conducting fluid into such vessel. During the inhalation of air by a person he is to place on the hole *e* his forefinger of the hand by which he may have hold of the vessel. Should the vapors inhaled be too pungent, he can, by raising his finger off the hole, let fresh air into the vessel, and thereby modify the vapors or mix air with them so as to diminish their potency.

I do not claim an inhaler as made with nose-tubes to project from an air-inlet tube to extend into the liquid-holding part or vessel.

I claim—

The improved inhaler as made of one entire piece of glass, in manner substantially as specified.

DWIGHT RUSSELL, M. D.
